UNITED STATES PATENT OFFICE.

ELMER G. WARE, OF BISBEE, ARIZONA.

SPARK-PLUG PROTECTOR AND CLEANER.

1,203,943.

Specification of Letters Patent. Patented Nov. 7, 1916.

Application filed February 2, 1916. Serial No. 75,752.

To all whom it may concern:

Be it known that I, ELMER G. WARE, a citizen of the United States, and a resident of Bisbee, in the county of Cochise and State 5 of Arizona, have invented a new and Improved Spark-Plug Protector and Cleaner, of which the following is a full, clear, and exact description.

My invention has for an object to provide 10 a device applicable to a spark plug when the latter is not in use and adapted to engage the threaded cylindrical portion of the spark plug, and form a fluid-tight bearing against the shoulder at the base of the said 15 threaded portion, the said device forming a reservoir for gasoline, alcohol, or like liquid, the device thereby serving, when applied to the plug, to remove any carbon, dirt, etc., adhering to the plug and forming 20 at the same time a protector for the electrodes.

The invention will be particularly explained in the specific description following.

Reference is to be had to the accompanying 25 drawings forming a part of this specification in which similar reference characters indicate corresponding parts in all the views.

Figure 1 is a side elevation partly in section of a protector and cleaner formed in accordance with my invention, showing the same applied to a spark plug; Fig. 2 is a longitudinal section of the said protector and cleaner; Fig. 3 is a side elevation showing a modified form of protector and cleaner adapted to receive two spark plugs; Fig. 4 is a longitudinal section of the device shown in Fig. 3, the dotted lines indicating two spark plugs.

Referring more particularly to Figs. 1 and 2, my improved device consists of a hollow body 10 having internal threads 11 at one end adapted to engage the threaded cylindrical portion A of a spark plug B. The opposite end 12 of the body 10 is closed and the device has a length between the threaded portion 11 and the end 12 to constitute a reservoir for holding gasoline, alcohol, a carbon remover, or the like. When the body

10 is screwed tightly on the plug B the open 50 end thereof will form a fluid-tight contact with the shoulder C of the spark plug at the base of the threaded portion A. Thus the device will serve to protect the electrodes of the spark plug and serve to thoroughly 55 clean the plug and remove any carbon thereon. The body 10 has a wrench hold 13 formed thereon, here shown as hexagonal, to receive an ordinary wrench for turning the body in securing it to the plug B or removing it 60 therefrom.

In the forms shown in Figs. 3 and 4, the hollow body 10^a has both ends open and is formed with internal threads 11^a at each end. At an intermediate zone on the hollow 65 body 10^a, a wrench-hold 13^a is formed, here shown as hexagonal to receive a wrench similar to the wrench-hold 13.

In using the device as shown in Figs. 3 and 4, a spark plug B is screwed into each 70 end of the body 10^a until the ends of the body come respectively to a bearing against the shoulders C of the respective plugs. Thus, one plug seals each end of the body 75 10^a. The length of the body between the threaded portions 11^a is sufficient to constitute a reservoir for the cleaning liquid which thus acts upon both plugs.

Having thus described my invention I claim as new and desire to secure by Letters 80 Patent:

1. A protector and cleaner for spark plugs, including a hollow body open at both ends, each end being interiorly threaded, the threads being of a length and character 85 to take directly onto the threaded portion of a spark plug, the end edges being adapted to make a fluid-tight contact with the shoulder at the threaded portion of the spark plug, said body constituting a chamber for a 90 cleaning liquid between the said threaded portions.

2. A protector and cleaner for spark plugs, including a hollow body open at both ends, each end being interiorly threaded, the threads being of a length and character to 95 take directly onto the threaded portion of a spark plug, the end edges being adapted to

make a fluid-tight contact with the shoulder at the threaded portion of the spark plug, said body constituting a chamber for a cleaning liquid between the said threaded portions, the body furthermore having exteriorly thereon a zone forming a wrench-hold intermediate the ends of the body.

In testimony whereof I have signed my name to this specification in the presence of two subscribing witnesses.

ELMER G. WARE.
